C. D. BONSALL

CAR ROOF

Filed April 28, 1923

Inventor:
James David Bousell,
by Court Name,
his Attorney.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed April 28, 1923. Serial No. 635,234.

To all whom it may concern:

Be it known that I, CHARLES DAVID BONSALL, a citizen of the United States, and a resident of the city of Pittsburgh, in the county of Allegheny and State of Pennsylvania, have invented a certain new and useful Improvement in Car Roofs, of which the following is a specification.

This invention relates to car roofs of the flexible outside type wherein metal roof sheets extend from ridge to eaves of the car and are loosely secured to the car and to each other and are movably held in position at the ridge by ridge seam covers or separate retaining members upon which the roof sheets rock or oscillate in accommodating themselves to the distortions of the car frame.

The principal object of the present invention is to provide a simple and efficient ridge seam construction that will secure oscillatory movement of the sheets around the middle of their ridge ends without the use of separate pivot members and without affecting the weather-proofing qualities of the ridge seam construction. Another object is to prevent damage to the sheets during such movement. Other objects are cheapness of construction and compactness of design.

The invention consists principally in forming the seam flanges of the ridge seam covers with portions having tangential contact with the opposite sides of the ridge seam flanges of adjacent sheets, whereby said sheets are adapted to rock or oscillate about the contacting portions of the ridge seam covers in accommodating themselves to the distortions of the car frame and are prevented from both relative and joint bodily movement transversely of the car. The invention further consists in the parts and in the arrangements and combinations of parts hereinafter described and claimed.

In the accompanying drawing, which forms part of this specification and wherein like symbols refer to like parts wherever they occur.

Fig. 1 is a plan view of a portion of a car roof embodying my invention;

Fig. 2 is an enlarged vertical cross-section through one of the transverse seams on the line 2—2 in Fig. 1;

Fig. 3 is a vertical cross-section through the eaves portion of the roof, the section

being taken adjacent to a transverse seam on the line 3—3 in Fig. 1;

Fig. 4 is a vertical cross-section through the ridge midway of a transverse seam on the line 4—4 in Fig. 1;

Fig. 5 is a vertical cross-section through one of the ridge seam caps; and,

Fig. 6 is a plan view of a portion of one of the ridge seam caps, a portion of the top wall of the cap being shown broken away to disclose the portions of the seam flanges that function as pivots for the roof sheets to turn on.

Referring to the accompanying drawing, my invention is shown applied to the ordinary type of car roof comprising side sheathing 7 and roof sheathing 8, which is supported at the eaves on side plates 9 at the ridge by means of a ridge pole 10. Metal roof sheets 11 are arranged in pairs on opposite sides of the ridge. Each pair of roof sheets is spaced from adjacent pairs at their sides, and between the spaces thus formed are arranged mullions or battens 12. The mullions extend transversely of the car from eaves to eaves of the car and are of less width than the space between side margins of adjacent sheets.

The eaves ends of the roof sheets 11 are loosely secured to the substructure by means of angle flashing strips 13. These flashing strips rest in a rabbet formed in the eaves ends of the roof sheathing 8 and extend from end to end of the car, passing beneath the eaves ends of the mullions 12. The vertical flange of each eaves flashing strip 13 is nailed or otherwise rigidly secured to the side of the car, and the portion of the strip resting in the rabbet is doubled back upon itself, as at 14. The eaves ends of the roof sheets 11 are doubled under, as at 15, and are hooked into the doubled back portion 14 of the eaves flashing strip 13.

The side and ridge margins of the roof sheets 11 are flanged up and turned in and down forming downwardly and inwardly hooked upstanding side and ridge seam flanges 16 and 17, respectively. The side marginal seam flanges 16 of the roof sheets adjacent to the mullions 12 are covered by transverse seam caps 18 of substantially inverted channel-shaped cross-section. The transverse seam caps 18 straddle the mullions 12 and the side marginal flanges 16 of adjacent sheets and have inwardly and

upwardly extending hooked flanges 19 adapted to interlock with said side seam flanges 16. The eaves ends of the top portions of the transverse seam caps 18 are provided with extensions 20 that are bent down over the eaves ends of the mullions 12 and are thence turned under the adjacent doubled under flanges 15 of the roof sheets 11 located on each side of the mullions and 10 thus serve to loosely secure the eaves ends of the roof sheets to the car.

Ridge seam covers 21 of substantially inverted channel-shaped section straddle the ridge seam flanges 17 of each adjacent pair 15 of roof sheets 11 and have inwardly and upwardly curved lower side marginal portions 22 that rest upon the body portions of the roof sheets 11 between the transverse seam covers 18. The adjacent ends of the 20 ridge seam covers 21 and the transverse seam covers 18 are held in position on the usual pan-shaped four-way center or corner caps 23 having openings in each of their four walls to receive the adjacent ends of 25 said ridge and transverse seam caps. The corner caps 23 are secured to the substructure by means of bolts 24, which also secure the running board saddles (not shown) in position.

30 The curled lower side marginal portions 22 of the ridge seam covers 18 are formed midway of their ends with extensions or tabs in the form of raised rebent flanges that are bent upwardly and are thence curved outwardly and downwardly to form 35 hollow ribs 25 of substantially inverted U-shaped section which overlap and embrace the middle portions of the spaced ridge seam flanges 17 of oppositely arranged 40 sheets. The side walls of each rib 25 of a ridge seam cover 21 are bowed in opposite directions from each other (that is, from the middle towards each end), thus forming oppositely curved surfaces in the sides 45 of the grooves or channels formed by said hollow ribs, whereby the distance between the opposing side walls of each downwardly opening groove is a minimum midway of the groove and increases gradually towards 50 each end thereof. The width of the grooves midway of their length corresponds to the width of the ridge seam flanges 17, whereby said grooves snugly embrace said flanges and thus maintain a proper spacing of the 55 ridge ends of the roof sheets and prevent bodily movement of said sheets crosswise of the car.

By reason of the double convexity of the 60 grooves in the hollow ribs 25 of each ridge seam cover, each side of a groove has a line contact with the adjacent side of the ridge flange or rib 16 of a roof sheet, with the result that each roof sheet has pivotal 65 tangential contact with both walls of the groove in the hollow rib of a ridge seam

cap, whereby said roof sheets are permitted to oscillate about the engaging or contacting portions of the hollow ribs of the ridge seam cover in response to the weaving of the car frame.

The invention is not restricted to the forms and arrangements shown and described.

What I claim is:

1. A flexible car roof comprising movably mounted roof sheets spaced apart along their adjacent margins and having raised portions extending along said margins, and a seam cover secured to the car and straddling the raised portions of adjacent sheets, said seam cover having portions that extend downwardly between the roof sheets and portions that extend downwardly over the body portions of said roof sheets adjacent to said raised portions, said downturned portions engaging the opposite sides of said raised portions for only a slight distance whereby sluing of the sheets is permitted and bodily movement thereof towards and away from each other is prevented. 90

2. A flexible car roof comprising roof sheets spaced apart along their adjacent margins and having hollow ribs extending lengthwise thereof, and a seam cover straddling the ribs of adjacent sheets and having tangential contact with both walls of each of said ribs. 95

3. A flexible car roof comprising roof sheets spaced apart along their adjacent margins and having hollow ribs extending lengthwise thereof, and a seam cover straddling the ribs of adjacent sheets and having contact with both walls of each of said ribs along one line only. 100

4. A flexible car roof comprising roof sheets spaced apart along their adjacent margins and having ribs extending lengthwise thereof, and a seam cover straddling the ribs of adjacent sheets and having contact with both walls of each of said ribs for a portion of their length only. 105

5. A flexible car roof comprising roof sheets spaced apart along their adjacent margins and a seam cover spanning the margins of adjacent sheets, the adjacent margins of said sheets being provided with raised ribs and said seam cover being provided with groove portions whose side walls have tangential contact with said ribs respectively, thereby permitting sluing of the sheets and preventing bodily movement thereof towards and away from each other. 115

6. A flexible car roof comprising roof sheets spaced apart along their adjacent margins and having ribs extending lengthwise thereof, and a seam cover secured to the car and straddling the ribs of adjacent sheets, said seam cover being provided with hollow ribs that straddle the ribs of adjacent sheets and engage both sides of said 130

roof sheet ribs for a portion of their length only.

7. A flexible car roof comprising roof sheets spaced apart along their adjacent margins and having raised rebent flanges extending lengthwise thereof, a seam cover straddling the flanges of adjacent sheets and having raised rebent flanges that cooperate with said roof sheet flanges, the side walls of said seam cover flanges having tangential contact with the side walls of said roof sheet flanges.

8. A seam cover for a car roof, said

seam cover being of substantially inverted channel-shaped section and being provided with a plurality of hollow ribs that are wider at the ends than at the middle.

9. A seam cover for a car roof, said seam cover being of substantially inverted channel-shaped section and having extensions at the lower edges of its side walls that are formed into hollow ribs of greater width at the ends than at the middle.

Signed at New Kensington, Pa., this 23 day of April, 1923.

CHARLES DAVID BONSALL.
